AUTOMATIC LUBRICATION SYSTEM FOR KNITTING MACHINES

James H. Yon, Jr., Charlotte, N.C., assignor to Jett Manufacturing Corporation, Charlotte, N.C., a corporation of North Carolina

Filed Feb. 12, 1968, Ser. No. 10,550

Term of patent 14 years

U.S. Cl. D46—1
Int. Cl. D23—01

FIGURE 1 is a perspective view of an automatic lubrication system for knitting machines embodying my new design;

FIGURE 2 is a side view of the automatic lubrication system for knitting machines of FIGURE 1; and

FIGURE 3 is a rear view of the automatic lubrication system for knitting machines of FIGURE 1.

The dominant features of my design reside in those portions shown in full solid lines in the drawing.

I claim:

The ornamental design for an automatic lubrication system for knitting machines, as shown and described.
